UNITED STATES PATENT OFFICE.

FREDERICK W. HENNINGER, OF DETROIT, MICHIGAN.

RECORDING DEVICE FOR DISPENSING APPARATUS.

1,291,874.

Specification of Letters Patent. Patented Jan. 21, 1919.

Application filed September 1, 1917. Serial No. 189,273.

To all whom it may concern:

Be it known that I, FREDERICK W. HENNINGER, a citizen of the United States of America, residing at Detroit, in the county 5 of Wayne and State of Michigan, have invented certain new and useful Improvements in Recording Devices for Dispensing Apparatus, of which the following is a specification, reference being had therein to the action 10 accompanying drawings.

The invention relates to recording devices for dispensing apparatus and is more particularly designed for use in connection with the dispensing of hydrocarbon oil and other liquids. It is the object of the invention to produce a record which will indicate each time the dispensing apparatus is operated and the particular individual it is operated by. It is a further object to produce a record which cannot be altered and which is beyond the access of the individual operating the apparatus.

In the drawings:

Figure 1 is a perspective view of the recorder, showing the connection between the same and the dispensing apparatus;

Fig. 2 is a side elevation of the recorder with the casing removed;

Fig. 3 is an end elevation thereof;

Fig. 4 is a plan;

Fig. 5 is a perspective view of a portion of the recorder detached;

Fig. 6 is a perspective view of another portion thereof.

Fig. 7 shows a fragmentary portion of the record strip as it is perforated by operation of the machine.

The recorder may be operated by any suitable connection with the dispensing apparatus, but as shown A is the reciprocating rack-bar of a dispensing apparatus and B is a flexible band, the end of which is secured to said rack-bar and which passes into the casing C into engagement with a drum D therein. This drum is provided with a spiral spring E for re-winding the band, and there is also provided a stop mechanism which determines the normal position of parts. This, as shown, is formed by a gear-wheel F on the drum which is in mesh with a pinion G, and co-operating stops H and H' on said pinion and gear determine the initial position by causing said wheels to bind. As these stops will not come into registration again during the maximum movement of the drum under actuation of the band

they will not interfere with the movement but will merely insure a predetermined starting point.

The drum D also carries a pawl I' which engages a ratchet-wheel J independently revoluble about the same axis, and this ratchet-wheel is connected with a train of gears K K' K² for communicating motion to a shaft L. Upon the shaft L is mounted a pair of perforating wheels M M' which are opposite paper-holding reels N N' on the shaft of the drum D. O is a rotary head in which are mounted a series of cooperating perforating wheels P P', etc., which by 60 rotatively adjusting said head may be brought into co-operation with the perforating wheels M M'. The head O is mounted on a shaft Q, which also carries a head R having a series of locks S mounted thereon 65 and in alinement with the rolls P. Each of the locks S is rotatively operable only upon the insertion of a properly fitting key which will permit it to turn. Each lock also carries at its inner end a member T 70 adapted in one position of adjustment of the lock to release a dog U which locks the gear-wheel F from movement. The position assumed by one of the members T to release the dog U is shown in Fig. 3 in dash lines. 75

With the construction as thus far described the dog U by holding the gear-wheel F from movement prevents any actuation of the drum D, so that the first operation required in the use of the apparatus is 80 to unlock the same. This unlocking can be accomplished by any one of the keys for fitting the several locks, it being necessary for the operator to insert the key, rotate the head O to a position where the engaged lock is adjacent to the shaft L, and then to 85 turn the key to operate the member T, releasing the dog U. As soon as the dog U is thus released the recorder is in condition for operation, and each stroke of the rack-bar A will draw the band B, rotating the drum D. The movement of the drum will be transmitted through the dog I' to the ratchet-wheel J and from the latter through the gear-train K K' K² to the shaft L. This 90 will revolve the perforating wheels M and M' which will advance the paper tapes Z and Z' from the reels N and N' and also perforate the same. The return stroke of the rack A will permit the band B to be wound up upon the drum D by the action of the spiral spring E, but this movement is not 95 100 105 110

transmitted to the gear-train as the pawl I' is slipped over the ratchet-wheel and a dog I engaging said ratchet-wheel and mounted upon a frame V will hold the same 5 from movement in the reverse direction. To make the desired record it is necessary that there should be an individual mark corresponding to each key which is used. This is accomplished by placing a different 10 number of perforating points upon each of the rolls P P', etc., which points also perforate the tapes Z and Z' in addition to the perforations placed therein by the rolls M or M'. For instance, one of the rolls P 15 may be adapted to form a single line of perforations, another a double line, another a triple line, etc. Furthermore the perforations produced by these rolls in each of the two tapes are the same so that the record 20 made upon one tape is an exact duplicate of the other. One of the tapes as Z' is kept permanently in the machine and is only open to inspection upon removing the case, but the other tape Z passes out through a slot M² 25 in the casing and can be torn off to be used as a sales slip. To permit of thus removing the sales slip, I have provided means for rolling the tape Z from the perforating rolls, and to preserve the permanent record 30 I have provided means for rolling up the tape Z', the construction being as follows: The drum D and rolls M M' are mounted on the frame V, which also carries the gear-train K K' K² and shaft L, but which is independent of the shaft Q³. This frame V 35 is pivotally mounted upon a shaft W and normally stands in a position where the rolls M M' are separated from the rolls P. When, however, the band B is drawn, the frame V will be lifted, swinging about the pivotal support W and moving the rolls M M' into contact with the rolls P, so that the tapes Z and Z' passing therebetween will be correspondingly perforated by the perforators 40 on both sets of rolls. On the other hand, when the band B is re-wound upon the drum and returns to its initial position the lifting force is withdrawn and the frame V, together with the shaft L and rolls M M' will 45 drop away from the rolls P. Thus in the normal position the tapes Z and Z' are released from the perforating rolls and the tape Z can be drawn out through the slot M² and torn off. 50 The reeling of the permanent record tape Z' is effected by winding it upon a drum X, (see Fig. 6) which is driven by a gear-train Y from the train K'. The movement transmitted by this driving connection is more 55 than sufficient to take up the tape Z', but a friction connection between the drum X and the gear-wheel Y' prevents overstraining said tape.

With the construction operating as described, it will be understood that an unmis-

takable check or tally is kept of each individual sale. Thus any one of the operators who has possession of a key may unlock the recorder and use the dispensing apparatus, but a record is made both on the tape Z that 70 is thrown out and upon the permanent retained tape Z' which individualizes this sale. Should the salesman attempt to give a false record by altering the check which is taken from the machine or destroying it, this fraud 75 will be detected and the permanent record inspected.

What I claim as my invention is:

1. A recording instrument, comprising mechanism for advancing a tape, a series of 80 individual perforators for operating on said tape, means for locking said mechanism from operation, a series of locks corresponding to the individual perforators, and means actuatable through each of said locks when the 85 corresponding perforator is in operative relation to said tape for unlocking said mechanism.

2. A recording instrument, comprising means for advancing a tape, a series of 90 individual perforators alternatively adjustable into operative relation to said tape, a series of locks corresponding to the individual perforators, means for locking said mechanism from operation, and means operable by each 95 of said locks only when a corresponding perforator is adjusted into operative relation to said tape for unlocking said mechanism to permit the advance and perforation of the 100 tape.

3. A recording instrument, comprising means for simultaneously advancing a pair of tapes, a series of pairs of individual perforators alternatively adjustable into operative relation to the pairs of tapes, a series 105 of locks corresponding to the individual perforators, means operable by each of said locks only when the corresponding pair of perforators is in operative relation to the pair of tapes for unlocking said mechanism 110 to permit the advance and perforation of the tapes, and a housing in which one of said tapes is inclosed slotted for the discharge of the other of said tapes.

4. A recording instrument, comprising a 115 casing, means housed within said casing for simultaneously advancing a pair of tapes, an actuating connection for said advancing means operable from outside the casing, means within the casing for locking said 120 advancing mechanism from operation, a series of pairs of perforators alternatively adjustable into operative relation to said pairs of tapes, a series of locks corresponding to said pairs of perforators, means operable by each of said locks only when the corresponding pair of perforators is in operative 125 relation to the pair of tapes for unlocking said advancing mechanism to permit the advance and perforation of said tape, 130

- and means for retaining one of the tapes within said housing and permitting the discharge of the perforated portion of the other of said tapes.
5. A recording instrument, comprising a housing, mechanism within said housing for advancing a pair of tapes, an actuating connection for said mechanism operable from outside of said housing, means within said 10 housing for locking said mechanism from operation, a series of individual perforators for operating simultaneously on each of said tapes, said perforators being alternatively adjustable into operative relation to said 15 tapes, a series of locks corresponding to the individual perforators, means operable by said locks only when the corresponding perforator is in operative relation to said tapes for unlocking said mechanism to permit the 20 perforation of said tape, means for automatically releasing one of said perforated tapes within said housing when not actuated, and means for discharging the perforated portion of the other of said tapes from said 25 housing.
6. In a recording instrument, the combination with a casing, of mechanism within said casing for simultaneously advancing a pair of tapes, said mechanism being operated from outside the casing, means within 30 said casing for locking said mechanism from operation, a rotary member within said casing adjustable from outside thereof, a series of individual perforators mounted on said 35 rotary member alternatively adjustable by the rotation thereof into operative relation to the pairs of tapes, a series of locks corresponding to the individual perforators and carried by said rotary member in alignment with their respective perforators, and means operable through each of said locks when said rotary member is adjusted to bring the perforator corresponding to the lock in operative relation to said tapes for 40 unlocking said mechanism to permit the advance and perforation of said tapes.
7. In a recording instrument, the combination with a casing, means within said casing for simultaneously advancing a pair 45 of tapes, means for locking said mechanism from operation, a rotary member within said casing rotatable from the outside thereof, a series of individual perforators mounted on said rotary member and alternatively 50 registerable by the rotation thereof with said pair of tapes, a series of locks corresponding to said individual perforators carried by said rotary member in alignment with the respective perforators, means operable by each of said locks only when said 55 rotary member is adjusted to register the corresponding perforator with said tapes for unlocking said mechanism to permit the advance and perforation of said tapes, means 60 for operating said mechanism from outside

said casing adapted to initially adjust said tapes into contact with the coöperating perforator and to release the tapes from the perforator upon the completion of the advancement, whereby the perforated portion 70 of one of said tapes may be withdrawn from said casing.

8. A recording instrument, comprising mechanism for advancing a tape, a series of individual devices for marking said tape, means for locking said mechanism from operation, a series of locks corresponding to the individual marking devices, and means actuatable through each of said locks when the corresponding marking device is in operative relation to said tape for unlocking 75 said mechanism.

9. A recording instrument, comprising means for advancing a tape, a series of individual marking devices alternatively adjustable 80 into operative relation to said tape, a series of locks corresponding to the individual marking devices, means for locking said mechanism from operation, and means operable by each of said locks only when a 85 corresponding marking device is adjusted into operative relation to said tape for unlocking said mechanism to permit the advance and marking of the tape.

10. A recording instrument, comprising 90 means for simultaneously advancing a pair of tapes, a series of pairs of individual marking devices alternatively adjustable 95 into operative relation to the pairs of tapes, a series of locks corresponding to the individual marking devices, means operable by each of said locks only when the corresponding pair of marking devices is in operative 100 relation to the pair of tapes for unlocking said mechanism to permit the advance and marking of the tapes, and a housing in which one of said tapes is inclosed slotted for the discharge of the other of said tapes.

11. A recording instrument, comprising a casing, means housed within said casing for simultaneously advancing a pair of tapes, an actuating connection for said advancing means operable from outside the casing, means within the casing for locking said advancing mechanism from operation, a series of pairs of marking devices alternatively adjustable into operative relation to said pairs of tapes, a series of locks corresponding to said pairs of marking devices, means operable by each of said locks 115 only when the corresponding pair of marking devices is in operative relation to the pair of tapes for unlocking said advancing mechanism to permit the advance and marking of said tape, and means for retaining 120 one of the tapes within said housing and permitting the discharge of the marked portion 125 of the other of said tapes.

12. A recording instrument, comprising a housing, mechanism within said housing for 130

- advancing a pair of tapes, an actuating connection for said mechanism operable from outside of said housing, means within said housing for locking said mechanism from 5 operation, a series of individual marking devices for operating simultaneously on each of said tapes, said marking devices being alternatively adjustable into operative relation to said tapes, a series of locks corresponding to the individual marking devices, means operable by said locks only when the 10 corresponding marking device is in operative relation to said tapes for unlocking said mechanism to permit the marking of 15 said tape, means for automatically releasing one of said marked tapes within said housing, and means for discharging the marked portion of the other of said tapes from said housing.
- 20 13. In a recording instrument, the combination with a casing, of mechanism within said casing for simultaneously advancing a pair of tapes, said mechanism being operated from outside the casing, means within said 25 casing for locking said mechanism from operation, a rotary member within said casing adjustable from outside thereof, a series of individual marking devices mounted on said rotary member alternatively adjustable by 30 the rotation thereof into operative relation to the pairs of tapes, a series of locks corresponding to the individual marking devices and engageable with said rotary member in alignment with their respective marking devices, and means operable by each of said locks when said rotary member is adjusted to bring the marking device corresponding to the lock in operative relation to said tapes for unlocking said mechanism to 35 40 permit the advance and marking of said tapes.
14. In a recording instrument, the combination with a casing, means within said casing for simultaneously advancing a pair of 45 tapes, means for locking said mechanism from operation, a rotary member within said casing rotatable from the outside thereof, a series of individual marking devices mounted on said rotary member and alternatively 50 registerable by the rotation thereof with said pair of tapes, a series of locks corresponding to said individual marking devices carried by said rotary member in alignment with the respective marking devices, means 55 operable by each of said locks only when said rotary member is adjusted to register the corresponding marking device with said tapes for unlocking said mechanism to permit the advance and marking of said tapes, 60 means for operating said mechanism from outside said casing adapted to initially adjust said tapes into contact with the co-operating marking device and to release the tapes from the marking device upon the 65 completion of the advancement, whereby the

marked portion of one of said tapes may be withdrawn from said casing.

15. A recording instrument, comprising means for advancing a tape, a series of individual marking devices for operating on 70 said tape, a rotative holder for said marking devices, actuatable to selectively dispose said devices in operative relation to said tape, a locking device for said tape advancing means, and key-controlled members for releasing said locking devices respectively corresponding to the individual marking devices. 75

16. A recording instrument, comprising means for advancing a tape, a series of individual marking devices for operating on 80 said tape, a rotative holder for said marking devices, actuatable to selectively dispose said devices in operative relation to said tape, a locking device for said tape advancing means, and key-controlled members for releasing said locking devices respectively corresponding to the individual marking devices, and actuatable in unison with said marking devices to establish any of said members 90 in operative relation to the locking device when the corresponding perforating device is in operative relation to the tape. 85

17. A recording instrument, comprising means for advancing a tape, a series of individual marking devices for operating on 95 said tape, a rotative holder for said marking devices, actuatable to selectively dispose said devices in operative relation to said tape, a locking device for said tape advancing means, key-controlled members for releasing said locking device, a rotative holder for said members, and means connecting the holders for the perforating devices and for said key-controlled members, effecting shifting of a certain key-controlled member into 100 operative relation to the locking device when the corresponding perforating device is in operative relation to the tape. 105

18. A recording instrument comprising a 110 pivotal frame, a shaft mounted in said frame substantially parallel to its pivotal axis, a parallel shaft independent of said frame, perforating means for perforating an advancing tape jointly carried by said shafts, 115 a drum carried by the first-mentioned shaft, and a flexible member adapted to wind on and off of said drum and to pivotally displace said frame to establish operative engagement of the perforating means and tape 120 when said flexible member is tensioned.

19. In a recording instrument, the combination with a casing, of mechanism within 125 said casing for advancing a tape, said mechanism being operated from outside the casing, means within said casing for locking said mechanism from operation, a rotary member within said casing adjustable from outside thereof, a series of individual perforators mounted on said rotary member alterna- 130

tively adjustable by the rotation thereof into operative relation to the tape, a series of locks carried by said rotary member and respectively corresponding to the individual 5 perforators and means operable through each of said locks when said rotary member is adjusted to bring the perforator corresponding to the lock in operative relation to said tape for unlocking said mechanism to 10 permit the advance and perforation of said tape.

20. In a recording instrument, the combination with a casing, means within said casing for advancing a tape, means for locking 15 said mechanism from operation, a rotary member within said casing rotatable from the outside thereof, a series of individual perforators mounted on said rotary member and alternatively registerable by the rota-

tion thereof with said tape, a series of locks 20 corresponding to said individual perforators carried by said rotary member in alinement with the respective perforators, means operable by each of said locks only when said rotary member is adjusted to register the 25 corresponding perforator with said tape for unlocking said mechanism to permit the advance and perforation of said tape, means for operating said mechanism from outside said casing adapted to initially adjust said 30 tapes into contact with the coöperating perforator and to release the tape from the perforator upon the completion of the advancement, whereby the perforated portion of said tape may be withdrawn from said casing. 35

In testimony whereof I affix my signature

FREDERICK W. HENNINGER.
